INSTRUMENT BOARD LAMP

Filed July 15, 1927

Inventor:
Harry A. Douglas
by G. H. Grayatty.

UNITED STATES PATENT OFFICE.

HARRY A. DOUGLAS, OF BRONSON, MICHIGAN.

INSTRUMENT-BOARD LAMP.

Application filed July 15, 1927. Serial No. 206,026.

My invention relates to cowl lamps in which the cowls enclose or surround electric incandescent lamp bulbs and are furnished with openings which serve to define paths for the light emanating from the bulbs. The lamp structure of my invention is of particular use when mounted upon the dash or instrument board of an automotive vehicle.

A prior lamp structure of this general class included a horizontal elongated oval shaped base, an incandescent lamp bulb mounted thereon, a correspondingly shaped rounded front hood or cowl mounted on the base and enclosing the lamp, the hood or cowl being provided with a sector shaped opening in its lower front portion to widen the path of the light, and a convex shutter pivotally mounted at its ends within the cowl and in one position adapted to completely close the opening of the cowl and to supplement the rounded front end thereof. My invention has for its general object the elimination of the base on which the cowl and lamp bulb are both mounted, this object being accomplished by forming or uniting the cowl and the lamp bulb socket in a unitary structure, one of these elements, preferably the cowl, being secured to the mounting board and carrying the other. In the prior device the oval shaped base was attached to the mounting board independently of the cowl and lamp socket and served as a mounting for the cowl and socket.

My invention has as another feature the provision of a sectional shutter for the light emitting opening of the cowl. The employment of this shutter enables the use of a narrower cowl whose light emitting opening is sufficiently wide to enable the insertion of the thumb and finger tips therethrough into the interior of the cowl, when the shutter is fully open, for the purpose of replacement of the lamp bulb. The shutter is desirably formed in two sections arranged in shingle fashion, both sections being mounted to turn upon a common axis extending longitudinally of the cowl, the shutter sections being adapted to turn with respect to each other in both the opening and closing movements of the shutter. The invention, however, is not to be limited to the employment of the sectional shutter, as will be apparent.

The invention will be more fully explained by reference to the accompanying drawing, in which Fig. 1 is a sectional view on line 1—1 of Fig. 2, illustrating the preferred embodi-

ment of the invention, the sectional shutter being unfolded to cover the light emitting opening in the cowl; Fig. 2 is a front elevation of the structure shown in Fig. 1; Fig. 3 is a section view on line 3—3 of Fig. 2; Fig. 4 is a sectional view on line 4—4 of Fig. 3; Fig. 5 is a view on a larger scale of a part of the structure illustrated in Fig. 1, showing the sectional shutter in folded adjustment 65 and in an open position and omitting a finishing washer, this figure indicating the lamp bulb, by dotted lines, in its passage through the cowl opening; and Fig. 6 is a perspective view illustrating the cowl and lamp socket 70 in one unitary structure and the finishing washer in separated relation thereto.

The cowl 1 is of any suitable shape. As illustrated, it is oblong and has flat top and bottom sides which are joined by semi-cylindrical end portions 2 and 3 and a rounded front portion 4. The light emitting opening 5 extends lengthwise of the cowl but terminates, at each end, short of the semi-cylindrical portions 2 and 3 since it is found that this opening need not be sector shaped when the structure is used upon the dash board of an automobile. The lamp socket 6, preferably metallic, is provided with a flange 7 at its front end, this flange being preferably square in contour and having two opposite edge portions in close contact with and preferably soldered to the top and bottom sides of the cowl, this flange desirably having continuations or aprons 8 and 9 extending at right angles to the body thereof and in extended contact with the top and bottom sides of the cowl, these flange portions 8 and 9 being soldered to the cowl. The socket flange 7 is desirably received within an annular recess 10 provided at the forward end of the socket 6 which is near the rear of the cowl. The front end of the socket is provided with bayonet slots or channels 11 which are adapted to receive the bayonet pins or projections 12 extending radially from the base 13 of an incandescent lamp bulb 14, this bulb being entirely within the interior of the cowl when its base is fully assembled with said socket. I have illustrated a single pole lamp in which one terminal of the filament is suitably connected with the base 13 of the lamp bulb which is, in such event, metallic to have electrical contact with the metallic socket 6 that is suitably grounded. The other terminal of the 110 filament is connected with the contact button 15 that is provided upon and insulated from

the rear end of the base 13. The lamp socket 6 encloses a coiled spring 16 and two insulating washers 17 and 18 between which the spring is interposed, the rear washer 18 being seated upon the inturned rear end of socket 6 and the forward washer 17 carrying a contact 19 which is pressed, by the spring 16, into electrical engagement with the contact 15. The circuit wire 20, by means of which 10 the lamp filament is included in circuit, terminates in the contact 19.

The unitary structure comprising the united elements 1 and 6 is mounted upon the instrument board or other mounting 21 by 15 attaching means provided upon one of these elements. In the preferred embodiment of the invention, the attaching means comprises two ears 22 which are integral continuations of the cowl and are preferably provided at 20 the base of the cowl. These ears are formed with perforations 23 through which the threaded stems of attaching bolts 24 are passed, these bolt stems passing through openings in the mounting board 21 and receiving clamping nuts 25 which engage the rear of the mounting board. In furnishing the lamp structures of my invention to the manufacturers of automotive vehicles, I also supply the anchoring bolts which are 30 carried by the ears 22, the nuts being in place upon the bolt stems. In attaching the structure it is only necessary to unscrew the nuts, pass the stems of the bolts through the mounting board, and reaply the nuts to 35 clamp the attaching ears 22 tightly against the mounting board. If preferred, a finishing washer 26 of dish form may receive the rear of the cowl, this finishing washer having openings 27 through which the bolt stems 40 are passed. This finishing washer is illustrated in each view excepting Fig. 5, the structure shown in Fig. 5 lacking this washer.

The opening 5 may be provided with a shutter to close or partially close said opening. When the lamp bulb 14 closely approaches the top and bottom sides of the cowl, the shutter is made in a plurality of sections, preferably two, 28 and 29, which are within the cowl and may be folded or 50 unfolded, such a shutter enabling the cowl opening 5 to be sufficiently wide in order that the tips of the thumb and finger may be inserted into the cowl for the purpose of replacing the bulb, Fig. 5 showing the shutter fully opened and with its sections together and indicating the bulb, by dotted lines, in the act of being passed through said opening. The shutter sections are cylindrical in curvature to conform in shape to the cylindrical front of the cowl. The shutter sections are provided with rearwardly extending ears 30 and 31 which are journaled upon coaxial pins 32 that are provided within the cowl and upon the curved end walls 2 and 3 60 thereof. Said pins are coaxial with the shut-

ter sections 28 and 29 and with the front portion of the cowl with which the shutter section 28 has snug sliding fit. The shutter section 29 is provided with a thumb and finger piece 33 that extends through the 70 opening 5 to the exterior of the cowl. When the shutter sections are being unfolded to close the opening 5, the thumb and finger piece 33 is pressed downwardly until, the ears 30 upon the shutter section 29 ultimately 75 engage the lugs 34 that project toward each other from the ears 31 whereby positive closing movement of the shutter section 28 follows after the shutter section 29 has been turned to a predetermined extent. 80

Spring ears 35 extending rearwardly from the rear edge of the shutter section 28 are adapted for engagement with the top of the cowl before the rear edge of the shutter section 28, during closing movement thereof, reaches the upper marginal edge 5' of the cowl opening 5, to frictionally resist any tendency of the shutter section 28 to move 85 towards closed position with the shutter section 29 sufficiently far to permit a gap to be 90 formed between the rear edge of the shutter section 28 and the edge 5' of the cowl opening, the frictional resistance of the ears 35 being adapted to be overcome, however, by the closing force exerted on the shutter section 28 by the shutter section 29 after the ears 30 of the latter engage the lugs 34 of the former. 95

The square flange 7 may, if desired, be formed with sloping wings 36 which project 100 toward the opening 5 and serve to intercept light passing from the bulb toward the rear of the cowl. Where the finishing washer 26 is employed, it is desirably loosely held in assembly, for convenience in storage and 105 shipment, with the socket and cowl preferably by means of a spring tongue 37 struck from the socket 6. If desired, this tongue may terminate short of said washer when the cowl is fully received within the washer, as 110 illustrated in Fig. 1.

Changes may be made without departing from the invention.

Having thus described my invention, I claim:

1. A lamp structure including an incandescent electric lamp bulb; a socket in which the base of the bulb is separably received; and a cowl surrounding the bulb and attached to said socket to form a unitary structure therewith, said unitary structure being provided with a formation whereby it may be attached to a mounting board and a finishing washer of dish formation assembled with the rear of the cowl, said socket being provided with a tongue between which and the cowl said finishing washer is interposed. 120

2. A lamp structure including an incandescent electric lamp bulb; a socket in which the base of the bulb is separably received; 125

and a cowl surrounding the bulb, said socket having a flange received within the cowl and secured thereto whereby the socket and cowl constitute a unitary structure, said unitary

5 structure being provided with a formation whereby it may be attached to a mounting board and a finishing washer of dish formation assembled with the rear of the cowl, said socket being provided with a tongue between 10 which and the cowl said finishing washer is interposed.

3. A lamp structure including a cowl, a lamp socket carried by said cowl, a finishing washer in closing relation to the rear of the 15 cowl, and means forming a connection between said lamp socket and said washer holding the latter in closing relation to the rear of the cowl.

4. A lamp structure including a cowl, a 20 lamp socket member carried by said cowl, a finishing washer member in closing relation to the rear of the cowl, and a spring tongue carried by one of said members for engagement with the other to hold the washer member in closing relation to the rear of the 25 cowl.

5. A cowl having a light emitting opening therein, a shutter for closing said opening comprising a pair of sections movable relatively to one another, cooperating means between said sections whereby one section following a predetermined amount of closing movement thereof positively imparts closing movement to the other section, and a friction 30 device operating during at least a portion of the closing movement of said last mentioned section to resist such movement.

6. A cowl having a light emitting opening therein, a shutter for closing said opening 40 comprising a pair of sections movable relatively to one another, cooperating means be-

tween said sections whereby one section following a predetermined amount of closing movement thereof positively imparts closing movement to the other section, and a spring 45 tongue carried by said last mentioned section for frictional engagement with said cowl during at least a portion of the closing movement of said last mentioned section to resist such movement. 50

7. A cowl having a light emitting aperture therein, a shutter for closing said aperture comprising inner and outer sections movable relatively into substantially complete overlapping relation with one another and into 55 the cowl to an open position with respect to said aperture, a finger grip member on the inner section for moving it to closed and open positions, formations on said sections, respectively, spaced apart when the sections are 60 disposed in substantially complete overlapping relation adapted to engage one another during closing movement of the inner section whereby closing movement of the inner section positively imparts closing movement 65 to the outer section, and a friction device carried by the outer section for cooperation with the cowl to resist tendency of said outer section to move with said inner section in a closing direction during at least the latter part 70 of the closing movement of said outer section.

8. A lamp structure comprising a cowl open at its rear end, a lamp socket permanently assembled with said cowl, a finishing 75 washer for closing the open rear end of said cowl, and means detachably connecting said finishing washer in closing relation to the open rear end of said cowl.

In witness whereof, I hereunto subscribe 80 my name.

HARRY A. DOUGLAS.
